Primary Examiner — Robert M Spear*Assistant Examiner* — Kendra L Hamilton**CLAIM**

I claim the ornamental design for a lid for a serving dish, as shown and described.

DESCRIPTION

FIG. 1 is a front perspective view of my new design for a lid for a serving dish, featuring the top, front and left sides thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof; and,

FIG. 7 is a bottom elevational view thereof.

The broken lines shown in FIG. 7 form no part of the claimed design.

1 Claim, 5 Drawing Sheets(56)
